G. L. WELLER,
DRINKING DEVICE,
APPLICATION FILED NOV. 10, 1919.

1,376,059.

Patented Apr. 26, 1921.

UNITED STATES PATENT OFFICE.

GEORGE L. WELLER, OF ELYRIA, OHIO.

DRINKING DEVICE.

1,376,059.

Specification of Letters Patent. Patented Apr. 26, 1921.

Application filed November 10, 1919. Serial No. 337,076.

To all whom it may concern:

Be it known that I, GEORGE L. WELLER, a citizen of the United States of America, residing at Elyria, in the county of Lorain 5 and State of Ohio, have invented certain new and useful Improvements in Drinking Devices, of which the following is a specification.

My present invention relates generally to 10 drinking devices, and more particularly to a sanitary drinking arrangement for use in connection with water receptacles in and around factories and the like where for instance there is no city water pressure, my object being the provision of a drinking fountain in connection with a fluid receptacle, which will avoid the use of cups and the like ordinarily used under similar circumstances in connection with open water buckets.

20 In my improvements as hereinafter described, a closed water vessel or container is formed when the parts are assembled complete for use, a drinking nozzle being included in these parts to which the drinking fluid is forced through a manually operated pumping action.

A further object of the invention is the provision of a device of this character in 30 which the discharge of waste fluid is readily taken care of without interference with the drinking operation, and in which the several parts are capable of ready disassembly and of effective cleaning when disassembled.

In the accompanying drawing which illustrates my present invention and forms a part of this specification,

Figure 1 is a central vertical sectional view through my improved apparatus,

Fig. 2 is a horizontal section taken substantially on line 2—2 of Fig. 1,

Fig. 3 is a top plan view.

Referring now to these figures, the fluid container or receptacle 10 is preferably of vertical cylindrical form with a closed base 45 11 and a reduced upper upwardly open neck portion 12, the latter of which is in use telescoped by a flanged cover 13 forming the support of the drinking device, this cover 13 having a central opening through 50 which a discharge pipe 14 is movable.

The discharge pipe 14 forms a hollow piston rod and has a threaded connection at its inner end with the upper chambered head 15 of a piston 16, the latter working in a

cylinder 17 between the base 18 of said cylinder and a series of limiting members 19 which prevent the piston 16 from being drawn upwardly and completely out of the cylinder 17.

The cylinder 17 is, in the effective position of the parts, located within the lower central portion of the container or receptacle 10 and is supported by virtue of the threaded connection at 20, of the lower ends of supporting rods 21, whose upper ends are secured by lock nuts 22 to the cover 13. The limiting members 19 before referred to are in the nature of washers held beneath lock nuts 23 on the lower portions of the supporting rods 21 against the adjacent portions of the cylinder 17, while the lock nuts 22 have threaded connection with the upper portions of the rods 21 and engage the inner and outer faces of the cover 13.

The chambered upper portion 15 of the piston 16 which is in open communication with the lower end of hollow piston rod or discharge pipe 15 has a lower constricted valve seat 24 on which a ball valve member 25 is seatable, this ball valve being freely movable in the chambered portion of the piston so as to open in an upward direction when the piston 16 is forced downwardly in the cylinder 17.

Centrally of its base 18, cylinder 17 has a slotted valve cage 26 provided with a lower valve seat 27 and containing a ball valve member 28 which seats downwardly on the seat 27 and opens upwardly to permit of intake of fluid from the container or receptacle 10 and into the cylinder 17 when the piston 16 is drawn upwardly.

The upper outer end of the hollow piston rod or discharge pipe 14, projecting above the cover 13 at all times, has an upper reduced extremity forming a discharge nozzle 29 in fixed relation within an upwardly flaring fountain cup 30, the latter having its base 31 secured around the upper outer portion of the discharge pipe 14 and receiving the threaded inner ends of radially outstanding discharge pipes 32, which form handles by which the discharge pipe or hollow piston may be moved upwardly and downwardly. The outer ends of the discharge pipes 32 are 100 preferably down-turned as at 33 beyond the side limits of the container or receptacle 10 so that the waste overflow from the nozzle

29 into the fountain cup 30 will be carried off by the pipes 32 and discharged beyond the container or receptacle to avoid all danger of waste fluid finding its way into the 5 container or receptacle.

It is obvious that by virtue of the support of the pumping arrangement in connection with the cover 13, the entire operating parts may be removed by simply lifting the cover 10 vertically from the container or receptacle. This permits of readily washing the interior of the container or receptacle, which it will be noted is entirely free of interior projecting parts or obstructions likely to interfere 15 with its cleaning and it is also obvious that removal of the operating parts permits of ready cleaning of these parts, as well as the interior of the receptacle or container.

In operation with the parts assembled, as 20 seen in Fig. 1, it is simply necessary to grasp the handles 32 and raise the discharge pipe 14 so as to shift the piston 16 upwardly within the cylinder 17. During this movement, the piston valve 25 is closed and suction 25 opens the cylinder valve 28 and draws the fluid inwardly of the cylinder 17 from the fluid receptacle or container. The discharge pipe and its parts are then pressed downwardly and during this movement 30 which forces the piston 16 downwardly in the cylinder, the valve 25 opens and the water previously sucked into the cylinder will be forced upwardly through the hollow piston rod or discharge pipe and out of 35 its upper nozzle 29, for drinking purposes, the waste being caught within the fountain cup 30 and discharged through the hollow handles forming discharge pipes as previously described.

40 It is thus to be seen that I provide a sanitary arrangement which will do away with the ordinary drinking cup and the usual open drinking bucket, and that my invention is applicable alike to stationary and 45 portable fluid containers or receptacles. I have shown the invention in connection with a readily portable container or receptacle and it is preferable that the waste be simply discharged upon the surface of the ground. 50 In connection with stationary receptacles it is obvious on the other hand that a waste receptacle may supplement the fluid container, receiving the discharge from the downturned discharge ends 33 of the hollow 55 handles or discharge pipes 32.

I claim:

1. The combination with a receptacle or container having an upper open end, of a cover for the said upper open end forming a support, a pumping discharge device extending into the receptacle or container and supported in its entirety by and removable with the said cover, said pumping discharge device including a vertically movable discharge pipe projecting exteriorly through the cover, and waste collecting and discharging means at the outer end of the discharge pipe and movable therewith, as described. 60

2. The combination with a fluid container or receptacle, of a pumping or discharge device including a cylinder, a piston working in the cylinder, a hollow piston rod engaging the piston at its inner end and having its outer end projecting exteriorly of the 75 receptacle or container to form a discharge pipe, a fountain cup at the outer end of the discharge pipe, and waste discharge pipes leading from the said fountain cup and forming handles whereby the hollow piston 80 rod may be moved inwardly and outwardly in action.

3. The combination with a fluid container or receptacle, having an upper open end, a cover for the upper open end of said receptacle or container having supporting rods depending thereon, an upwardly opening cylinder carried by the inner ends of said rods, a piston shiftable vertically in the said cylinder, a hollow piston rod, the inner end 90 of which is secured to the piston and the outer end of which is mounted through the cover, a fountain cup in connection with the external end of the hollow piston rod to catch the discharge therefrom and waste 95 discharge pipes radiating from the said fountain cup and forming handles for the manipulation of the hollow piston rod in use. 85

4. The combination of pumping means including a vertically movable hollow pump 100 rod forming a discharge pipe for the products of the pumping action and having a nozzle at its upper end, a fountain cup around the nozzle, and discharge pipes leading from the cup and forming handles 105 for the manipulation of the pump rod in use.

In testimony whereof I affix my signature.

GEORGE L. WELLER.
